UNITED STATES PATENT OFFICE.

GEORGE E. WARREN, OF SWAMPSCOTT, MASSACHUSETTS, ASSIGNOR TO UNITED SHOE MACHINERY CORPORATION, OF PATERSON, NEW JERSEY, A CORPORATION OF NEW JERSEY.

APPARATUS FOR USE IN HANDLING WELTING.

Original application filed June 27, 1919, Serial No. 307,129. Divided and this application filed January 8, 1921. Serial No. 435,911.

The present invention relates to apparatus for use in handling welting and more particularly to an apparatus which is adapted to be employed in connection with a welt 5 shoe sewing or other machine for operating on welting to protect the welting while it is being supplied to the machine.

Welting is usually supplied to the shoe manufacturer in a length of about twenty yards which is laid in a coil or hank and is tied up in this form for storage or transportation. It is customary to transport these hanks in an uncovered condition in which the welting is subject to soiling and injury. When the welting is to be used, a day's supply consisting of several hanks is issued to the welt sewing machine operator. Before use, the hanks are immersed in water and when they have soaked sufficiently, the surplus water is drained off and the hanks are then placed on the bench or on the floor behind the machine and the leading end of one of the hanks is inserted in the welt guide of the machine. Each of these hanks 25 contains sufficient welting for sewing about twenty pairs of shoes of medium size. When the hank from which the welt is being drawn is nearly exhausted so that there is not enough welting to sew another shoe, it is necessary either to splice the end of another hank to the part of the hank left in the machine or to remove the short length of the first hank from the machine and insert the leading end of another hank in 30 the welt guide.

Obviously when this method is followed, the welting applied to successive shoes will vary greatly in condition. The welting which is first used will usually be excessively wet, after which its condition may improve as the water dries from the surface and permeates more evenly the body of the welting, and later it will dry out and become relatively stiff. The condition of the 45 welting is a very material factor in the production obtained from the welt sewing machine. If the welting is too wet the fact annoys the operator and he is apt to work slowly or wait until it is in better condition. When the welting becomes too dry, it does 50 not run properly to the machine, particularly at the end of the toe where it often curls up and can be straightened out only with considerable difficulty. The improper

condition of certain parts of the welting 55 may interfere with or prevent the proper formation of the seam or the proper attachment of the welting to the shoes and thus result in imperfections in the finished 60 shoes.

When the welting is spliced by the operator, the splicing requires considerable skill and care and is often improperly done causing imperfect work. In cases where the welting is not spliced, the short lengths 65 of welting containing less than enough for a single shoe left at the end of each hank are usually wasted, thereby adding considerably to the expense of manufacture.

The object of the present invention is to 70 provide an apparatus for handling welting which is adapted to maintain the welting in a uniform moistened condition, particularly while it is being supplied to a welt shoe sewing or other machine.

With this object in view, the invention contemplates the provision of a receptacle for the reception of a bag or package of welting with the upper portion of the bag turned back over the rim of the receptacle, 80 and a tapered cover for the receptacle having an opening in its upper end for the passage of the welting from the receptacle, the cover having its lower portion arranged to extend within the receptacle inside of 85 the bag and having a flange on its lower portion to rest on the bag at the point where the bag passes over the rim of the receptacle to cooperate with the lower portion of the cover extending within the receptacle to 90 hold the margin of the bag in position with relation to the receptacle. The package of welting above referred to may be employed in carrying out the method described and claimed in United States Letters Patent No. 95 1,552,588, granted Sept. 8, 1925, upon an application of which the present application is a division.

The opening in the cover of the receptacle permits the welting to be withdrawn from the receptacle and fed to a welt shoe sewing machine by the welt feeding devices of the machine. The covered receptacle restricts the circulation of air about the package of welting and protects it from the heat of the sewing machine, so that the mass of welting is thereby maintained in a uniformly moistened condition. The tapering cover of the 100 105

receptacle extends upwardly a considerable distance to protect the welting during its passage to the sewing machine.

The several features of the present invention will be clearly understood from the following description and accompanying drawings, in which:

Figure 1 is a side elevation of a portion of a welt grooving and beveling machine with a bag for receiving the welting as it issues from the machine, and a bag holder applied thereto which may be used in connection with the improved apparatus; Fig. 2 is a detail vertical sectional view of the bag holder illustrated in Fig. 1; Fig. 3 is a side elevation of a package of welting which may be used in the improved apparatus; and Fig. 4 is a vertical sectional view, partly in elevation, of the improved apparatus with a package of welting contained therein.

The improved apparatus may be employed in carrying out the method described and claimed in the above mentioned Letters Patent. In carrying out this method, mechanism is employed for arranging a strand of welting in a mass within a fabric bag to form a package of welting such as the one forming the subject matter of an application filed of even date herewith. This mechanism, as illustrated, is embodied in a welt grooving and beveling machine of the type illustrated and described in the patent to Morrill, No. 1,309,583, dated July 8, 1919. The welt grooving and beveling machine is provided with a rotating welt guide 10 mounted on a vertical axis within a hollow pedestal 12 forming a part of the frame of the machine. The pedestal 12 is mounted on a stand 14 provided with upright supports or legs 16. Between the legs of the stand is secured a bag holder 18 consisting of a sheet metal cylinder adapted to be inserted in the mouth of the bag. The bag for the reception of the welting, which is indicated at 20, is placed between the legs of the stand 14, and the upper end of the bag is drawn over the end of the bag holder so that the bag holder will hold the mouth of the bag distended. In order to hold the bag in position on the bag holder, a series of spring clips 22 are secured to the bag holder beneath which the upper margin of the bag may be inserted. With this construction, as the welting is delivered progressively to the welt guide from the welt grooving and beveling machine, the welt guide will deposit the welting within the bag in a mass without definite or regular arrangement of coils, but giving a twist to the welting during each revolution of the guide so that the welting will run freely from the mass without tangling or twisting when it is withdrawn progressively therefrom.

In the further carrying out of the method of said Letters Patent, the coil or mass of

welting within the bag is wet several hours before the welting is to be used, preferably by immersing the bag with the welting therein in water. Then after draining off the surplus water, the bag of welting is set aside and the welting allowed to mull within the bag, the bag restricting the circulation of air through the welting and protecting it from surface drying. At the end of a few hours, the water will have uniformly penetrated the body of the welting, producing a thoroughly mulled and cheesy condition. When in this condition, the welting can be readily pierced by the sewing needle without tearing the fibres of the leather and can be readily shaped as required in attaching the same to the shoe.

When the welting is to be used, the bag with the welting therein is placed in the improved apparatus, forming the subject matter of the present application, which is located in a position convenient to the sewing machine, and the bag is opened and the leading end of the welting is inserted in the welt guide of the sewing machine. The improved apparatus is so constructed as to restrict the circulation of air about the bag and thereby prevent rapid drying of the bag and the welting therein. The apparatus comprises a cylindrical can 24 for the reception of the bag of welting, having a tapered cover 26 formed at its upper end with a relatively small opening 28 for the passage of the welting to the sewing machine. The diameter and height of the can 24 is preferably such that the bag will fill the can with the sides of the bag supported by contact with the interior of the can from the top to the bottom of the bag. The upper or marginal portion at the mouth of the bag may be turned back over the rim of the can, as shown in Fig. 4. Preferably, as indicated in Fig. 4 the bottom of the can is open as well as the top and the bag is adapted to rest upon the floor or other support upon which the can is placed. The lower portion of the cover is made with an inturned annular flange or shoulder which is adapted to rest upon the portion of the bag which extends over the rim of the can, and which terminates in a depending flange of such diameter, smaller than the diameter of the can, that the depending flange will extend within the bag and clamp the bag to the rim of the can so as to hold the bag in place. The tapered cover 26 extends upwardly a considerable distance to protect the portion of the welting extending to the sewing machine. As shown, the can may be open at the bottom as well as at the top to enable the can to be placed over the bag and thus avoid the necessity of lifting the bag in the can. It will be apparent that the improved apparatus will thus protect the welting from the drying conditions about the

sewing machine due to the heat of the machine and will maintain the welting in the proper moistened condition.

While it is preferred to employ the specific construction and arrangement of parts illustrated and described, it will be understood that this construction and arrangement is not essential except so far as specified in the claims, and may be changed or modified 10 without departing from the broader features of the invention.

The nature and scope of the present invention having been indicated, and an apparatus embodying the several features of 15 the invention in their preferred form having been specifically described, what is claimed is:—

1. An apparatus for use in handling welting having, in combination, a receptacle for 20 the reception of a bag of welting with the upper portion of the bag turned back over the rim of the receptacle, a tapered cover for the receptacle having an opening in its upper end for the passage of the welting 25 from the receptacle and having its lower portion arranged to extend within the receptacle inside of the bag, and a flange on the lower portion of the cover to rest on the bag at the point where the bag passes over the 30 rim of the receptacle to cooperate with the lower portion of the cover extending within the receptacle to hold the margin of the bag in position with relation to the receptacle.

2. An apparatus for use in handling welting comprising a cylindrical casing open at 35 both ends and adapted to stand upright upon a floor or bench, a permeable bag filling the casing with the sides of the bag supported

by contact with the interior of the casing from the top to the bottom of the bag and 40 with the bottom of the bag resting upon the floor or bench, the marginal portion at the mouth of the bag being turned outwardly over the top of the casing, and a cover adapted to close the mouth of the bag and clamp 45 the bag to the casing, the cover having a relatively small opening to permit withdrawal of the welting from the casing.

3. A receptacle for handling welting in the manner described, comprising a permeable bag for the welting adapted to hold it while it is tempered, a protective casing in which the bag is placed after tempering the welting, and a protective cover for the top of the casing having a conical portion extending upward to protect the welting as it is withdrawn, the bag being doubled back over the top of the casing and the cover being constructed with a shoulder to engage the portion of the bag which extends over the top of the casing and with a depending portion extending within the receptacle and cooperating with said shoulder to hold the margin of the bag in position with respect to the casing and cover. 55

4. A receptacle for handling welting comprising a permeable bag for the welting, a protective casing open at top and bottom for surrounding and supporting the bag, and a protective cover for the top of the casing, 60 the bag being doubled back over the top of the casing and the cover being constructed with a depending portion to fit within the bag to hold the sides of the bag in place. 70

GEORGE E. WARREN.
